THREE-LEGGED SUPPORT FOR MACHINE GUNS

Application filed April 16, 1928. Serial No. 270,249.

The invention relates to a three-legged support for machine guns, the said support being arranged in such a manner that the gun during firing can recoil to such an extent that any displacement of the support from the position in which it is placed may be avoided, since the entire gun by the recoiling motion slides rearward on the support in the plane in which it has been adjusted and, after completion of the recoil motion, is advanced again into the normal position. The support proper remains thus unaffected by the recoil motion of the gun, for which reason the accuracy of the firing will be as great as possible. The support itself is arranged in such a manner that one of its legs is directed forward, and two of the legs are directed rearward, and all the legs may be adjusted independently of each other, and may be swung inward alongside the stock, so that the support when folded together may easily be carried by the men during their advancement to or retreat from a position.

On the drawing:

Fig. 1 shows the support, in side elevation, with the gun attached thereto in firing position,

Fig. 2 the support, in top view, without the machine gun,

Figs. 3 and 4 the front guiding device for the gun on the support, in vertical longitudinal section and in cross-section, respectively,

Fig. 5 a section along the line V—V of Fig. 4,

Figs. 6 and 7 the rear guide of the gun on the support, in partly sectional top view and in section along the line VII—VII of Fig. 6, respectively, and

Fig. 8 is a side elevation of the device showing the same in position for anti-aircraft fire.

The support consists of a stock 1, Figs. 1 and 2, which is formed by two bars fitted each at front with a bearing 2 for a horizontal shaft 34, Figs. 3 and 4, which midways between the bearings 2 is encircled by a bearing block 35 for a trunnion 3, which is held in position in the bearing block by means of a ring 3' fixed on the lower end of the trunnion, and which is fitted at top with a guiding member 4 for a sliding rail 5. To the lat-

ter there is hinged a strapping device 6 in which the front end of the machine gun 7 may rest and remain attached. 8 is the front leg of the support and is adapted to swing about the shaft 34. The trunnion 3 is rotatable about its own axis in the bearing block 35 and in a bore 36 in the shaft 34. The latter is fitted at each end with an axial bore 42 and 43. In the bore 43, Fig. 4, there is inserted a bolt 37 which is encircled by a helical spring 49 maintained in compression between a head 50 on the bolt 37 and a ring 51 fixed by means of a pin 52 in the bore 43 of the shaft 34. At the end facing towards the right in Fig. 4 the shaft 34 is fitted with a neck 53 encircled by a sleeve 55 with a flange 54, the said sleeve being connected to the shaft 34 by means of a rod 56 disposed parallel to the axis of the shaft and engaging longitudinal grooves 60 and 61 in the shaft and the sleeve respectively, in such a manner that the latter cannot rotate relatively to the shaft, but the sleeve is free to slide on the shaft. The rod 56 is attached to the shaft 34 by means of the pin 52. On to the outer end of the bolt 37 there is screwed a nut 57 pressing against the end face of the sleeve 55. On the outside of the sleeve 55 there is provided a flange ring 44 fitted at two diametrically opposite points with projecting lugs 45. The flange ring is attached to the sleeve 55 by means of a pin 58 passing through the flange 54. The lugs 45, Fig. 5, fit into one or the other of two pairs of notches 46 and 47 in the outer edge of the corresponding bearing 2. Into the bore 42 of the shaft 34 there is screwed a plug 49. By this construction the bolt 37 is connected with the bearing 2 in the position shown in Fig. 1, in which position the projections 45 engage the notches 46 in said bearing. However, if the support is to be used in an upright position, as shown in Fig. 8, the position of the sliding rail 5 in relation to the stock 1 must be altered. Consequently, the bolt 37, together with the sleeve 55, is drawn to the right in Fig. 4, whereby the projections 45 are removed from the notches 46 in the bearing 2, whereupon the sleeve is turned until the projections 45 come opposite the notches 47 in said bearing and enter said notches, 100

The sliding rail 5 is then in the proper position with relation to the stock which is necessary for using the support in an upright position.

To the leg 8 there is hinged a rod 9 passing through a sleeve 10, which is disposed on the stock 1, Fig. 2, and in which the rod may be pinched by means of a pinching device 11. On the rod 9 there is disposed, between the sleeve 10 and a handle 12, a helical spring 13 serving to facilitate the return motion of the leg into folded position. The stock 1 is fitted, at rear, with a curved frame 14, and to each of the rear corners of the same a leg 15 is attached. Each of these legs is pivoted about its pin 16 and may be fixed to the frame 14 by means of a pinching device 17. The rear member 14' of the frame is fitted with a graduation 14", and two adjustable and fixable stops 18 and 19 are provided on the said frame member. The frame 14 serves as a guiding frame for a supporting frame 20 adapted to slide along the latter and to support the rear supporting post 21 of the gun 7, the length of which post may be increased or reduced in order to adjust the machine gun to the desired elevation. The bottom end of the supporting post 21 is connected to a sliding carriage 22 adapted to slide rearward or forward on the side pieces of the supporting frame 20, the end pieces 23 of the said carriage being sleeve-shaped, each encircling one of the side pieces which latter are formed each of two telescoping tubes 20' and 20", Figs. 6 and 7. In the side of the pipes 20' and 20" facing the central piece of the carriage there is provided a longitudinal slot 28 giving passage for a pin 24, Fig. 6, in firm connection with the central piece, the said pin being fitted inside of the side pieces with a flat head 25 engaged by two helical springs, viz an advancing spring 26 and a buffer spring 27. Each of the side pieces of the supporting frame is fitted at front with a shoe 29 resting against the front member of the frame 14. At rear the supporting frame 20 is fitted with a clip 30 which engages the rear frame member 14', and is adapted to be fastened thereto by means of a pinching device 31. The supporting frame 14 is further fitted with a handle 32 in which there is journalled a finger lever 33 connected to the trigger of the gun by means of a Bowden cable 38.

When the support is to be transported, the front leg 8 is folded up between the legs of the stock 1, while the rear legs 15 are swung up each alongside one of the bars of the stock. In this folded position the legs are secured by means of the pinching members 11 and 17, respectively. When thus folded together the support may be carried conveniently by one man introducing his arms below carrying straps 40 attached to eyelets 39 on the stock.

When the support is to be erected for action, the pinching devices 11 and 17 are released, and the front leg 8 is adjusted by means of the rod 9 in a suitable position, in which it is fixed by tightening the pinching device 11 against the rod 9. Each of the two rear legs 15 is then adjusted in the position fitting best to the ground, and is fixed by means of the pinching devices 17 while the sliding rail 5 is adjusted into the position shown in Fig. 1 in which the projections 45 on the sleeve 55 of the shaft 34 engage the notches 46 in the edge of the bearing 2. Finally the machine gun 7 is placed on to the thus erected support, the front end of the gun is fixed in the strapping device 6, and the butt-end is fixed to the supporting post 21, whereafter the elevation is adjusted by adjustment of the length of the supporting post 21. During the firing the machine gun moves alternately back and forth in the plane in which it has been placed, the supporting post 21 carrying along the sliding carriage 22 on the supporting frame 20, while the advancing springs 26 of the carriage become compressed when the latter is moved rearward and again advance the carriage and, thereby, the gun after the recoil motion. During the forward motion the springs 27 act as buffer springs. During this rearward and forward motion the sliding rail 5 slides on the guiding member 4, so that the motion of the gun during firing will have no effect on the support itself.

If the firing has to be performed automatically, the trigger of the gun is maintained pressed towards the rear by pressing the finger lever 33 against the handle 32. If during the firing the machine gun is to be moved, within certain limits, from one side to the other, then the pinching device 31 is released, and the supporting frame 20 may then be moved alternately to the right and to the left in the frame 14, against the stops 18 and 19 respectively.

Besides for firing in horizontal position the support may also be used, as hereinbefore stated, for firing against objects in the air and then in upright position, the legs 15 being swung so as to come in line with the stock, while the leg 8 is swung in between the bars of the stock, the supporting post 21 being at the same time detached from connection with the machine gun, as shown in Fig. 8. The sliding rail 5 is then adjusted in such a manner that the projecting lugs 45 of the sleeve 55 will engage the notches 47 in the bearing 2. This adjustment is effected by moving the sleeve 55 to the right in Fig. 4, whereby the helical spring 49 will be compressed. When the sleeve has been displaced so far that the lugs 45 come clear of the notches 46, then the sleeve, and thereby the shaft 34, is turned so far that the lugs 45 come opposite the notches 47 in the bearing 2, whereafter the helical

spring 49 returns the sleeve 55, and the lugs 45 enter then into the notches 47. The support is held in the upright position by one of the men, and the gunner may then freely move the gun all the way around the support, so that he may fire in all directions, while the gun is pivoted about the trunnion 3 which latter when the support is used in upright position will occupy a vertical position, same as in the position of the support shown in Fig. 1, while the firing may now be effected at any elevation desired, since the gun is solely connected to the support by means of the above mentioned trunnion.

Having thus described my invention, what I claim is:—

1. A support for machine guns, comprising a stock having at one end a bearing block and at its opposite end a curved frame disposed transversely of the stock, a trunnion mounted for rotation in said bearing block and carrying a guiding member, a rail mounted on said guiding member for sliding movement forward and rearward, a supporting frame mounted on said curved frame for movement transversely of the stock, a carriage mounted on said supporting frame for sliding movement longitudinally of the stock, a longitudinally adjustable supporting post secured to said carriage and adapted to support the rear end of a gun, and a clamping device carried by said sliding rail and adapted to clamp the gun in position at its opposite end.

2. A support for machine guns, comprising a stock having at one end a bearing block and at its opposite end a curved frame disposed transversely of the stock, a trunnion mounted for rotation in said bearing block and carrying a guiding member, a rail mounted on said guiding member for sliding movement forward and rearward, a supporting frame mounted on said curved frame for movement transversely of the stock, a carriage mounted on said supporting frame for sliding movement longitudinally of the stock, helical springs for actuating said carriage and helical springs acting as buffers for said carriage, a longitudinally adjustable supporting post secured to said carriage and adapted to support the rear end of a gun, and a clamping device carried by said sliding rail and adapted to clamp the gun in position at its opposite end.

3. A support for machine guns, comprising a stock having at one end a bearing block and at its opposite end a curved frame disposed transversely of the stock, three legs pivotally connected to said stock and adapted to be folded into approximate parallelism therewith, means for clamping said legs in folded and unfolded position, a trunnion mounted for rotation in said bearing block and carrying a guiding member, a rail mounted on said guiding member for sliding movement forward and rearward, a supporting frame

mounted on said curved frame for movement transversely of the stock, a carriage mounted on said supporting frame for sliding movement longitudinally of the stock, a longitudinally adjustable supporting post secured to 70 said carriage and adapted to support the rear end of a gun, and a clamping device carried by said sliding rail and adapted to clamp the gun in position at its opposite end.

4. A support for machine guns, comprising 75 a stock having at one end a bearing block and at its opposite end a curved frame disposed transversely of the stock, three legs pivotally connected to said stock and adapted to be folded into approximate parallelism 80 therewith, a sleeve carried by said stock, a bar hinged to one of said legs and passing through said sleeve, a clamping device carried by said sleeve for securing said rod with the legs in folded and unfolded position, a spring carried by the rod and adapted to facilitate the return of the legs to folded position, a trunnion mounted for rotation in said bearing block and carrying a guiding member, a rail mounted on said guiding member for sliding movement forward and rearward, a supporting frame mounted on said curved frame for movement transversely of the stock, a carriage mounted on said supporting frame for sliding movement longitudinally of the stock, a longitudinally adjustable supporting post secured to 90 said carriage and adapted to support the rear end of a gun, and a clamping device carried by 95 said sliding rail and adapted to clamp the gun in position at its opposite end.

5. A support for machine guns, comprising a stock having at one end a pair of bearings and at its opposite end a curved frame disposed transversely of the stock, a shaft 105 mounted in said bearings, a bearing block supported on said shaft, a leg pivoted on the shaft, a trunnion disposed in an opening in said shaft and carrying a guiding member, the shaft being adjustable in said bearings 110 thereby to permit variation of the position of the trunnion relative to the support, a rail mounted on said guiding member for sliding movement forward and rearward, a supporting frame mounted on said curved frame 115 for movement transversely of the stock, a carriage mounted on said supporting frame for sliding movement longitudinally of the stock, a longitudinally adjustable supporting post secured to said carriage and adapted to support the rear end of a gun, and a clamping device carried by said sliding rail and adapted to clamp the gun in position at its opposite end.

6. A support for machine guns, comprising 120 a stock having at one end a pair of bearings and at its opposite end a curved frame disposed transversely of the stock, a shaft mounted in said bearings, a helical spring normally retaining said shaft in a prede- 125

terminated relative position, means for changing the position of the shaft against the tension of said spring, a bearing block supported on said shaft, a trunnion mounted in an opening in said shaft, a guiding member carried by said trunnion, a rail mounted on said guiding member for sliding movement forward and rearward, a supporting frame mounted on said curved frame for movement transversely of the stock, a carriage mounted on said supporting frame for sliding movement longitudinally of the stock, a longitudinally adjustable supporting post secured to said carriage and adapted to support the rear end of a gun, and a clamping device carried by said sliding rail and adapted to clamp the gun in position at its opposite end.

In testimony whereof I have signed my name to this specification.
